UNITED STATES PATENT OFFICE.

FRANK BILLINGS, OF CLEVELAND, OHIO.

APPARATUS FOR CASTING METAL INGOTS.

SPECIFICATION forming part of Letters Patent No. 319,780, dated June 9, 1885.

Application filed February 11, 1885. (No model.)

To all whom it may concern:

Be it known that I, FRANK BILLINGS, a citizen of the United States, residing in Cleveland, Cuyahoga county, Ohio, have invented 5 certain new and useful Improvements in Apparatus for Casting Metal Ingots, fully described and represented in the following specification and the accompanying drawings, forming a part of the same.

10 The object of this invention is to transfer the fluid metal from the kettle or ladle to the bottom of the mold without any breaking up of the fluid-metal current and without any admixture of air; and my improvement consists, essentially, in the combination, with a 15 fluid-metal kettle or ladle having an aperture in the bottom, of an ingot-mold fitted to such aperture, and a movable bottom fitted to slide within the mold from its top downward, 20 as and for the purpose set forth.

With the means heretofore employed the metal has been dropped from a spout into the open mouth of the mold, the current of metal falling in contact with the atmosphere and 25 operating, as it fell into the mold or into its contents, to draw a large amount of air down into the mold and to mingle the same most intimately with the fluid metal. A similar effect is readily observed when pouring water from a pitcher into a glass, and is strikingly noticeable when a current of water is 30 precipitated into a taller vessel nearly filled with water, the air-bubbles being then seen to descend nearly to the bottom of the vessel, 35 and to rise therefrom as rapidly as the fluid will afterward permit. Such air-bubbles not only render the steel ingot spongy, but their presence excites chemical action with the carbon present, and generates considerable volumes of hydrogen and carbonic-oxide gases, 40 which are not usually able to escape from the fluid metal before the latter becomes chilled.

Various means of compressing the fluid metal and of diminishing the fall of the current in filling deep molds and of exhausting the air from the mold before pouring have been heretofore devised, to avoid the formation of spongy ingots, as in United States Patents Nos. 124,700, 298,661, and 298,662, and Reissue 50 No. 10,082; but none of these or other inventions entirely prevent the access of air to the fluid current, or operate to prevent the divis-

ion of the same and the entangling of the air with some of its particles.

My present invention includes some of the 55 apparatus heretofore patented to G. W. Billings in the patents just cited, especially the "descending bottom" fitted within a vertical ingot-mold, as shown in United States Patent No. 298,662; but it differs from the 60 same in uniting the bottom of the kettle with the mold, and in having a tight connection between the bottom of the kettle and the interior of the mold, so that the flow of the metal from the kettle to the mold is not only 65 unbroken, but completely protected from the atmosphere.

My invention will be understood by reference to the annexed drawings, in which Figure 1 is a vertical elevation of a mold provided with a movable bottom and hydraulic cylinder, and attached to a kettle having a heating-flue around it, the parts being shown in section where hatched. Fig. 2 is a similar vertical section of an apparatus for "pouring" 70 or filling a series of molds from one kettle at the same time, the molds being joined to the kettle by detachable fastenings, and elevated therewith during the filling operation by hydraulic cylinders. Fig. 3 is a plan of the kettle, with a dotted line at *x x* indicating the plane on which the section in Fig. 2 is taken.

The molds represented herein are assumed to be of metal or other suitable material, and to be made in sections when necessary for the 85 convenient removal of the ingot, and they may be fastened to the bottom of the ladle or kettle in any convenient manner, and detached therefrom when filled and when the ingot is sufficiently cooled.

The kettle herein may in some instances be a movable ladle suspended from a crane and raised vertically with the mold during the filling of the mold by the crane-gearing; or it may be part of a fixed mechanism, and movable vertically with a series of molds by steam or water power, as shown in Fig. 2; or it may be a fixture, and the mold be adjusted and secured beneath it with a movable bottom therein, as in Fig. 1, and the fluid metal may in 90 these two latter cases be supplied to the kettle from the furnace in any convenient manner. The kettle or ladle is in the drawings so constructed that the precise charge of metal

for the molds should be supplied thereto, and no means of disposing of a surplus is therefore shown herein; but it is obvious that such surplus could be tapped from the side of the 5 kettle, if desired, and that the mouth of the mold can be stopped up when full, if desired.

In Fig. 1, A is the mold; A', straps to hold its sections together, as is usual; B, the kettle; B', the aperture in its bottom leading to the 10 mold; B'', a collar on the bottom around such aperture to guide the mold into its place, and C a refractory lining within the kettle.

F is a brick jacket around the kettle, forming a flue connected with a furnace or supplied 15 with gas and air so as to maintain a combustion therein. The mold is sustained beneath the kettle by blocks D', resting on a bed, D'; and D'' are columns extending from the bed to support the kettle, straps being shown around 20 the mold such as are required when the mold is made in sections, and the head of the mold being shown in contact with the bottom of the kettle within the collar B'', and held thereto by flanges l and bolt l'.

E is the water-cylinder, fixed upon a platform, E', beneath the mold and concentric therewith, pillars E'' being extended from the bed to the platform to connect the two. e is a piston in the cylinder, e' the piston-rod, and e'' a head formed thereon and fitted to slide freely inside the mold, and shown in the figure as supporting a refractory or movable bottom plate, e', just below the bottom of the kettle, the plate being secured to the head by bolts and keys f.

A packing or stuffing box, g, is provided at the top of the cylinder, and inlet-pipes b b' and outlet-pipes c c' are provided, respectively, at the top and bottom of the cylinder, to regulate the flow of the water therein.

H is an accumulator supplied with hydraulic pressure by a pump-pipe, H', and h is a pipe leading from the same to three-way cock i, which is connected with both the inlet-pipes b b' and provided with a handle, b'', by which the water can be turned into either pipe and the piston e forced up or down at pleasure.

The outlet-pipes are also provided with discharge-cocks c' c'', the former being opened when the piston is forced upward to adjust the head e'', as shown in the drawings, and the latter being opened to regulate the speed at which the head descends under the load of fluid metal, the water employed to force the bottom e'' up being employed to sustain it in the position shown during the filling of the kettle B.

The apparatus is operated by adjusting the head e'' with the movable bottom e' close to the bottom of the kettle, and packing the joint between the edge of the plate e' and the aperture B' with ganister or other refractory material, as at e''. The kettle is then filled to a marked point with just the quantity of metal required to charge the mold, and the metal is then allowed to stand until as cool as it can be made to flow into the mold, when the dis-

charge-cock c' at the bottom of the cylinder is opened sufficiently to permit the descent of the head e'' at the highest speed consistent 70 with a quiet flow of the metal into the mold, so as to avoid any collision of the particles and the drawing of any air into the mold by the formation of vortices. By thus settling the metal in the kettle before drawing it into 75 the mold ample opportunity is afforded for the disengagement of any contained gases, as the kettle is much shallower than the mold and its surface of much greater extent; and the method of transferring it to the mold when 80 thus freed from gases is expressly adapted to avoid the intermingling of any air with the fluid metal in the transit, as the metal is only admitted to the mold in the exact ratio in which the capacity of the mold is increased, 85 and the movement of the false bottom or plate e'' is easily regulated to exactly the desired speed.

If desired, the cock c' may be automatically moved as the bottom or head e'' descends, and 90 the discharge-outlet gradually closed as the weight or head of fluid metal in the mold increases, and the pipes c and c' may be connected together, if desired, so that the water may flow from below the piston e to its upper 95 side as the piston moves downward, the regulating-cock being then placed in such connecting-pipe.

When the mold is filled and the metal therein cooled, the weight of the mold and ingot is 100 sustained by a crane or hoist, while the blocks D' are knocked out, after which the mold can be lowered clear of the collar B'' and removed to have the ingot extracted.

By maintaining combustion in the hollow 105 jacket F the metal can be kept hot for a longer period in the kettle before drawing it into the mold, and the most perfect freedom from air and gases in the product be thereby secured.

In Figs. 2 and 3 is shown an apparatus operating in just the reverse manner to produce the same effect, and adapted to fill any desired number of ingots at once. In this device the kettle B B is shown formed with a flat bottom and having five molds attached to 110 it by the same means as in Fig. 1, the fastening-bolt being omitted in the latter figures on account of the reduction in the scale of those figures. The kettle is sustained upon hydraulic plungers J, fitted to cylinders J' upon 115 a bed, K, and the false bottoms e'' e''' are affixed to stationary rods I, which are secured to the bed beneath the centers of the openings B' B' in the bottom of the kettle over each mold.

In operation the false bottoms fill or close 120 all the apertures, as shown in Fig. 2, during the filling of the kettle with metal, as at L, and the hydraulic plungers J are then forced upward, lifting the kettle with all the molds attached and drawing the metal into the molds 125 in the same manner as with the other apparatus.

The plan in Fig. 3 shows the apertures B' B' plainly, as well as the difference in the area

of the united molds and the kettle itself, by which it will be seen that an upward movement of the kettle so far as only one-tenth the length of the ingot will suffice to fill all the 5 molds.

While the metal is cooling in the molds the latter are sustained in their elevated position with the kettle, and the molds can then be taken apart and detached from the kettle, 10 leaving the ingots standing upon the heads of the rods I.

By making the apertures in the bottom of the kettle of suitable size, the latter can then be lowered with the ingots projecting upward 15 through them, and the ingots then be removed singly by suitable hoisting apparatus.

It is obvious that the means required for handling the molds, the ingots, and the kettles must vary with the size of ingots to be 20 made; but as such part of the apparatus is already well known, and is not an essential part of my invention, the same is not shown at all herein. Neither is my invention limited to the mechanical arrangement shown 25 herein for supporting and actuating the false bottom, as it is immaterial what means are used, provided the movements are effected in the manner described.

It is obvious that a "compression-plate" 30 could be inserted beneath the bottom of the kettle and the surface of the metal in the mold, as in the United States Patent No. 298,662, referred to above, and that means for exerting compression could then be applied to the 35 contents of the mold by the movable bottom, as in said patent.

I am fully aware of the process patent application, No. 155,646, filed herewith, for similar subject-matter, and hereby disclaim all that 40 may be allowed in the said application.

What I claim herein is—

1. The combination, with a fluid-metal kettle having an aperture in the bottom, of an ingot-mold fitted to such aperture, and a movable bottom fitted to slide within the mold, as 45 and for the purpose set forth.

2. The combination, with a fluid-metal kettle having an aperture in the bottom, of an ingot-mold fitted to such aperture, and a movable bottom fitted to slide within the mold 50 and to close the aperture from the kettle, as and for the purpose set forth.

3. The combination, with a fluid-metal kettle having an aperture in the bottom, of an ingot-mold fitted to such aperture, a movable 55 bottom fitted to slide within the mold, and means, substantially as described, for moving said bottom and drawing the metal from the kettle into the mold, as and for the purpose set forth.

4. The combination, with a fluid-metal kettle having an aperture in the bottom, of a removable mold secured thereto at the aperture, a movable bottom fitted to the mold, a cylinder having a piston attached to the movable bottom by a piston-rod, means for forcing the piston and bottom upward by hydraulic pressure, and an adjustable escape-cock at the bottom of the cylinder, to regulate the velocity of the piston's descent, as and for the purpose set forth.

In testimony whereof I have hereunto set my hand in the presence of two subscribing witnesses.

FRANK BILLINGS.
